UNITED STATES PATENT OFFICE.

ELBERT D. WEYBURN, OF COHOES, NEW YORK, ASSIGNOR TO WEYBURN MACHINE COMPANY, OF NEW YORK, N. Y., A CORPORATION OF NEW YORK.

FLEXIBLE SHAFT AND CASING THEREFOR.

SPECIFICATION forming part of Letters Patent No. 729,823, dated June 2, 1903.

Application filed August 14, 1901. Serial No. 72,023. (No model.)

To all whom it may concern:

Be it known that I, ELBERT D. WEYBURN, a citizen of the United States of America, formerly a resident of Chicago, Illinois, but now 5 of Cohoes, in the county of Albany and State of New York, have invented certain new and useful Improvements in Flexible Shafts and Casings Therefor, of which the following is a specification.

10 My invention relates to an improvement in flexible or pliable shafts and to the covers or sleeves therefor, my object being to improve the conditions and means for operating a shaft suspended from an overhanging transmitting 15 device and which is constructed of jointed parts fastened together to permit of flexibility and at the same time to retain strength and durability.

Flexible shafts have mostly been constructed 20 out of spring-wire that is twisted or wound in layers one upon the other. This makes them flexible, and they could be used in a bent or curved position. These shafts have ordinarily been incased or worked inside of 25 a coiled-spring cover or sheath. Both the shaft and the cover have possessed more or less spring tension, and when they were used in a bent or curved position it was necessary to use more muscular effort or strength than 30 if the shafts were in a normal or straight position when running. The spring tension of the shaft and case causes extra friction and also requires extra power to move them when in a bent or curved position. The extra friction 35 also destroys and wears the shaft and cover and soon makes them weak and worthless, thereby causing loss to the owner and operator. The wire shafts are also cumbersome and unwieldy, especially if made of a diameter 40 to insure strength.

I have contrived and made a pliable shaft from hollow joints, which I mill at the ends, and form jaws, into which I fit a twisted link, and these parts are fastened together with 45 screws or rivets. The hollow links and twisted links move together and have sufficient lateral side play to enable me to bend the knuckle-joints and get the required pliability for the purpose. There is no spring or tor-

sion in my new improved shaft. I incase the 50 shaft inside of a flexible metal case, which is made of a metallic ribbon or metal tape. The sides of this tape are made with the edges turned under, so as to interlap or overlap each other, and these overlapped edges form 55 a groove that is a trifle wider than the turned edges, and this admits of a side or lateral movement of the lapped edges and affords sufficient flexibility to permit the metallic case to be moved to the extent that a portion 60 may be in a horizontal position, while another part may be vertically disposed. There being no spring in the metal case, which is of cylindrical shape, it readily conforms to any angle or position it is put into and remains 65 where it is placed until put into another position. Therefore when the knuckle-jointed shaft is incased in the metallic case it will be seen that there is no resisting spring tension to overcome, and both the knuckle-jointed 70 shaft and the metallic case conform to all angles they are put into and are used with less effort and labor than other combinations heretofore used as flexible shafts and sheaths. The hollow joints are lighter in weight than if 75 made solid, and the hollow space inside is used as an oil-pocket to hold lubricant for the purpose of oiling the outside of the shaft. I place an absorbent material, such as sponge or cotton waste, inside of the hollow joint and saturate this with a suitable lubricant. When the jointed shaft is moving, its centrifugal force will distribute the lubricant over the surface of the twisted links and outside of the hollow joints and this will lubricate the inside surface of the metallic case. The twisted links being made so that only their thinnest edges 85 touch the metallic case, less than one-half of their surface is subject to friction, and having less than one-half of a solid shaft in size and 90 weight these contribute to the lasting properties of the shaft and case.

I am aware that shafts have been made with solid hinged links and cylindrical parts as well as gimbal-jointed parts to obtain 95 flexure; but I have never seen a shaft made of hollow parts and twisted links as I describe it. Therefore the invention consists

finally in the peculiar construction and arrangement of parts hereinafter described and definitely claimed at the end hereof.

My invention is illustrated in the accompanying drawings, in which—

Figure 1 is a side elevation of an overhanging suspension device with my improved knuckle-jointed shaft and flexible casing illustrated as supported thereby. Fig. 10 is a side view of my knuckle-jointed shaft. Fig. 3 is a side view of my twisted link. Fig. 4 is an end view of my twisted link. Fig. 5 is a sectional side view of my hollow knuckle-joint. Fig. 6 is an end view of my hollow knuckle-joint. Fig. 7 is a longitudinal side view of my metallic case.

Referring now to the details of the drawings by letters, A represents the ceiling or overhanging support, to which are connected 20 the post-brackets a^2 , which support a pulley-hanger b^2 at the left-hand end and a pulley-hanger b at the right-hand end. The first of these supports a driving-pulley k , from which power is transmitted through pulleys f and shaft L , journaled in the aforesaid hanger b , to a pulley p , carried by the lower end of said shaft L , and from said pulley p to a pulley K , rotating with a shaft I , and from this shaft, to a pulley S , journaled in a pulley-hanger F . 25 This pulley S is secured to a screw-ferrule R . The parts so far described form the subject-matter of an application filed on the 14th day of May, 1902, Serial No. 107,311, and therefore need no further description. The 30 parts comprising my invention are suspended from this screw-ferrule R and may be described as follows:

U is my improved half-twisted flat link, the ends of which are twisted so that the flat sides 40 are at right angles to each other. At x^2 the flat sides fit into the jaws that are made in the hollow joints at w^2 .

V is my hollow joint made with open jaws at each end, said jaws being made to hold the 45 flat sides of the twisted links V , and the walls in said jaws act as a support and bearing for said twisted links and take the strain and wear off of the screw or rivet that holds the two parts together. Inside of the joint V is 50 a lubricant absorbent W , which is intended to hold oil or lubricant and distribute the same when the shaft is in motion.

S is my flexible non-rotating case, broken open to show the overlapping edges $t t$, and these edges are turned under, so as to interlap or overlap each other, and the overlapped edges form a groove a trifle wider than the turned-under edges, which admits of a side or lateral movement of the lapped edges and affords sufficient flexibility to permit the metallic case to be moved to the extent that a portion may be in a horizontal position, while another part may be vertically disposed, as hereinbefore set forth. It is to be understood that this metallic casing is not of the 60 nature of a spring, but is movable to any position to which it is placed and remains there until it is moved into another position. Hence when the operator moves the cutter to one position there is absolutely no friction of the 65 parts of the casing until the operator moves the cutter to another position.

Having thus described my invention, what I claim, and desire to secure by Letters Patent, is—

1. A knuckle-jointed flexible shaft constructed of hollow joints with open jaws, in combination with flat twisted links fitting into the open jaws and means for securing said hollow joints and twisted links, substantially as described. 75

2. A knuckle-jointed flexible shaft constructed of hollow joints with open jaws, in combination with flat twisted links fitting into the open jaws, and means for securing 80 said hollow joints and twisted links, the aforesaid hollow joints having pockets adapted to receive an absorbent material for the purpose of oiling the parts, substantially as described. 85

3. A knuckle-jointed flexible shaft constructed of hollow joints with open jaws and flat twisted links fitting into said open jaws, means for securing said hollow joints and twisted links together, and a pliable metallic 90 tubular casing or non-rotating cylinder made of a tape or ribbon with overlapping edges permitting a lateral side movement or flexure as said shaft is moved from one position to another, substantially as described. 95
